DRESSING MASK

Jeanne Gautreaux, Houston, Tex.

Application June 23, 1941, Serial No. 399,331

3 Claims. (Cl. 2—174)

The invention relates to a dressing mask of the type which is adapted to protect the dress while it is being donned or removed so that the dress will not become soiled with cosmetics.

It often occurs that when one is donning or removing a dress that the dress brushes across the face and may become soiled with cosmetics. This is particularly true as to rouge and lip stick, as well as other creams and greases.

The present invention directs itself to a simple and economical mask or shield which can be quickly placed in position and removed so as to cover the face, and particularly the nose and lips so that the dress may not come in contact with the cosmetics.

It is one of the objects of the invention to provide a quickly removable mask.

Another object of the invention is to provide a dressing mask which is made up of a net material and carries a protective shield to cover the nostrils and lips.

Still another object of the invention is to provide a dressing mask which is shaped to the contour of the features and neck so that it will fit snugly in position and will not be readily dislodged in donning and removing the dress.

Still another object of the invention is to make a dressing mask of a plurality of pieces or sections which are shaped and fitted together to make a composite mask which will fit the contours of the features and neck.

Still another object of the invention is to provide a dressing mask having a shield portion to completely cover the nostrils and lips while the balance of the mask permits vision therethrough and ventilation.

Still another object of the invention is to provide a complete coverage of the face and neck, which is cool, comfortable and washable and which may be readily put on and taken off.

Other and further objects of the invention will be readily apparent when the following description is considered in connection with the accompanying drawing, wherein:

Fig. 1 is a perspective view of the mask in protective position.

Fig. 2 is a side view of one-half of the dressing mask.

Fig. 1 shows the mask as comprising a body 2 of a net or like material which is cool, comfortable and washable and thru which there may be a flow of air. This body 2 is made up of a piece 3 of material which has had a cut 4 made therein from the upper edge 5 down to a location at about 6. A V-shaped piece is removed and the

two edges sewed together so as to draw the upper portion 5 inwardly as regards the nose portion 7. This piece is curved on its upper edges as at 8 so that it approximately follows the contour of the face line of an individual, passing over from a location directly in front of and about the elevation of the lower part of the ear upwardly over the forehead and down to the other side in front of the main portion of the ear.

The lower edge of this piece 3 is curved at 10 to approximately follow the line of the jaw and extends inwardly at 11 around the point of the chin. The forward edge 12 is a solid piece of material which remained intact when the cut was made to the point 6.

The portion thus described fits over the forehead, eyes, nose, mouth and down to approximately the point of the chin. It will be noted that the single seam 13 where the cut was made is the sole operation which is required to shape the face portion of the mask. This face portion may have a band 15 of elastic or other material which can be quickly passed over the head as seen in Fig. 1 to draw the mask firmly over the face and to hold it in this position.

In order to cover the neck and assist in the protection of the gowns, four pieces of material such as 16, 17, 18 and another piece 19, which is the counterpart of the piece 16 are sewed together. These four pieces are so shaped that when they are sewed together as a composite member, they will have the contour of the neck. The piece 16 is curved at 21 so as to allow the positioning of the mask in front of the hair 22. A lobe 23 on the piece 16 affords protection over the side of the neck. The forward edge 24 of this side piece 16 is sewed to the front neck portion 17 by a seam 25. Both of these pieces are in turn joined to the lower edge 10 of the face piece so as to cover the neck up to the line of the jaw.

The two parts 18 and 19 are counterparts of 16 and 17 just described, with the parts 17 and 18 joined together with a seam 27 along the line of the throat. In order to pull the neck portion snugly into position, a strap or tab 28 is connected to the lobe portion 23. This tape 28 may be tied in back of the neck or it may be an elastic 50 such as may be stretched over the head and snapped into place.

All of the pieces thus described are made of a net like material, giving an open formation so that the mask will be cool and comfortable but yet will prevent the gown from coming into contact

with light cosmetics on areas of the face covered by the net like material.

It has been found that the greatest amount of protection is desired against the heavier and more permeable cosmetics and to this end a semi-circular piece of material 30 is arranged, as seen in Fig. 1, to overlie the lips. This piece of material is attached in any suitable manner, such as by means of seams along the lines 11 and 31 whereby it is attached to the pieces 3, 17 and 18. The seam 31 passes proximate the nostrils a short distance below the end of the cut-out portion. This piece may be of any suitable material, such as cloth, paper or similar material so as to form a more or less impervious covering for the lips. This is the only closed portion of the entire mask and occupies but a small space sufficient to afford protection against heavy cosmetics, such as lip stick.

It seems obvious that the parts can be so proportioned as to give the size but it has been found in practice that where the design fits the general contour of the features, that the size is not material and that an ordinary size mask can be used by almost every person.

Broadly the invention contemplates a dressing mask which is cool, comfortable, washable and which can be readily attached or removed.

What is claimed is:

1. A dressing mask of net or like material including a plurality of shaped pieces of material and comprising a single piece cut and shaped to fit the forehead and over the nose, four additional pieces shaped to fit the neck line and chin, and a substantially semi-circular piece of opaque imperforate fabric material attached to the net material to cover the lips, and means to hold the mask on the head.
2. A protective mask or shield for use while dressing to prevent soiling of the clothing with cosmetics which comprises an impervious covering for the lips, and a net mask to closely fit the face and neck of an open net material, said mask carrying said covering so as to firmly hold the covering in place.
3. A protective mask or shield for covering the face while dressing to prevent soiling of the clothing with cosmetics which includes a covering comprising an area of material which is relatively impervious to heavy cosmetics and adapted to cover the lips where heavy cosmetics are applied, and a net mask to closely fit the face and neck to protect clothing from lighter cosmetics and carrying said covering so as to hold the covering over the lips.

JEANNE GAUTREAUX.
